US00D864937S

(12) **United States Design Patent** (10) Patent No.: **US D864,937 S**
(45) Date of Patent: **** Oct. 29, 2019**

(54) **CASE FOR ELECTRONIC DEVICE**

- (71) Applicant: **SPIGEN KOREA CO., LTD.**, Seoul (KR)
(72) Inventor: **Dae-Young Kim**, Seoul (KR)
(73) Assignee: **SPIGEN KOREA CO., LTD.**, Seoul (KR)

(**) Term: **15 Years**

(21) Appl. No.: **29/612,026**

(22) Filed: **Jul. 27, 2017**

Related U.S. Application Data

(63) Continuation of application No. 29/593,707, filed on Feb. 10, 2017, now Pat. No. Des. 807,338, which is a continuation of application No. 29/568,017, filed on Jun. 14, 2016, now Pat. No. Des. 788,760, which is a continuation of application No. 29/568,020, filed on Jun. 14, 2016, now Pat. No. Des. 791,116, which is a continuation of application No. 29/568,021, filed on Jun. 14, 2016, now Pat. No. Des. 786,233, which is a continuation of application No. 29/495,236, filed on Jun. 27, 2014, now Pat. No. Des. 771,607.

CLAIM

The ornamental design for a case for electronic device, as shown and described.

DESCRIPTION

FIG. 1 is a front perspective view of a case for electronic device showing my new design;

FIG. 2 is another front perspective view thereof;

FIG. 3 is a rear perspective view thereof;

FIG. 4 is a front elevational view thereof;

FIG. 5 is a rear elevational view thereof;

FIG. 6 is a left side elevational view thereof;

FIG. 7 is a right side elevational view thereof;

FIG. 8 is a top plan view thereof; and,

FIG. 9 is a bottom plan view thereof.

The broken lines depict of unclaimed environment and form no part of the claimed design. The dash-dot lines in the figure drawings represent the bounds of the claimed design.
